DESIGN FOR A CEREAL JAR

Anthony J. Desimone, Lyndhurst, N. J., assignor
to Columbia Protektosite Co., Inc., Carlstadt,
N. J., a corporation of New Jersey

Application December 11, 1944, Serial No. 116,826

Term of patent 7 years

(Cl. D58—25)

To all whom it may concern:

Be it known that I, Anthony J. Desimone, a citizen of the United States and resident of Lyndhurst, in the county of Bergen and State of New Jersey, have invented a new, original and ornamental Design for a Cereal Jar, of which the following is a specification, reference being had to the accompanying drawing, forming a part thereof, and of which Figure 1 is a front elevational view of a cereal jar showing my new design; Fig. 2 is a top plan view thereof; and Fig. 3 is a bottom plan view thereof.

I claim:

The ornamental design for a cereal jar, substantially as shown.

ANTHONY J. DESIMONE.
